UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

ELECTRODE.

1,212,610.

Specification of Letters Patent. Patented Jan. 16, 1917.

Application filed January 31, 1914. Serial No. 815,600.

To all whom it may concern:

Be it known that I, CHARLES W. DAKE, a citizen of the United States, residing at Chicago, in the county of Cook and State 5 of Illinois, have invented a certain new and useful Improvement in Electrodes, of which the following is a specification.

When it is necessary in arc lighting to keep the electric arc fixed in position as, for 10 instance, in connection with locomotive headlights where it is essential that the arc remain at the focal point, experience shows that it is desirable to use for one of the electrodes, preferably the negative, a copper 15 or other metallic member whose characteristic is that it is but slowly consumed by the arc. Since only a slight displacement of the arc is allowable, it is, therefore, necessary to provide means for warning the operator 20 when the negative electrode has been too greatly consumed. With this end in view I provide the lamp with automatic means for notifying the operator when the useful limit of consumption of the electrode has 25 been reached. In my preferred form I insert into the body of the electrode a device which notifies the operator by changing the color of the arc and subsequently by extinguishing the arc so that he not only 30 knows what is needed but absolutely must comply with the requirement.

My invention relates, therefore, to improvements in electrodes for arc lamps and the like and is illustrated in one form in the 35 accompanying drawing, wherein—

Figure 1 is a side elevation in part section of the two electrodes showing diagrammatically the wiring connections; Fig. 2 is a side elevation of the metallic electrode; 40 Fig. 3 is a bottom plan view; Fig. 4, a section similar to the section shown in Fig. 1, showing the electrode partly consumed; and Fig. 5, a similar section showing the electrode burnt out.

Like numerals refer to like parts throughout the several figures.

1 is a negative electrode for an arc lamp made of copper or other suitable material, the only requirement being that the metal 50 or material of which it is made be a conductor and one which is but slowly destroyed by the operation of the arc. 2 is a positive carbon rod or pencil electrode.

3 is a conductor leading from the positive

electrode 2 to the generator 4, and 5 is a 55 conductor leading from the generator 4 to the negative electrode 1.

The negative electrode 1 is made of a cylindrical shank C terminating in an expanded conical head A which head has a 60 base B upon which it is adapted to rest to fix it in position. The shank C together with the head A is cored or drilled as indicated. The bottom of the hole which extends almost to the apex of the cone contains a conducting plug D of some material preferably of metal such as lithium or strontium which when acted on by the open arc will change the color of the arc.

E is an insulating plug of asbestos or 70 other suitable material which, when the arc has consumed the plug D, will extinguish the arc.

F is a metallic plug of any suitable conducting metal to close the hole and hold the 75 plugs D and E in position.

The use and operation of my invention are as follows: The lamp aside from the two electrodes I have not shown as any suitable electrode controlling means of any kind 80 whatever might be used. The metallic negative electrode is, of course, adapted to be fixed in position resting upon the base of the cone. It is this electrode which is used up and then thrown away. The distance 85 from the top of this electrode to the surface of the insulating plug is the maximum distance through which the arc may be displaced without disastrous consequences. As

the light operates, the carbon or positive 90 electrode will be fed down, being gradually consumed. The metallic or negative electrode will be consumed but not so rapidly. This consuming of the negative electrode will continue until a crater is opened up 95 somewhat similar to that shown diagrammatically in Fig. 4, exposing the upper conducting plug. The arc will be formed then through and across this plug and the color will be changed radically, preferably to a 100 bright red, although other materials producing different colors might be used. This continues until the plug is consumed down to the insulating plug, and the presence of this insulating plug, of course, interrupting 105 the current will break the arc and the light will go out. The operator having previously seen the colored light will know when the

2
light goes out what is the matter and will instantly remove the burnt out negative electrode and replace it by a new one, whereupon the lamp can again be used. I have 5 suggested the use of such metals as lithium or strontium because they do give a bright red light which is unmistakably noticeable and most likely to warn the operator, although other materials might be used. The 10 same is true of the asbestos plug. This is a good insulator, and it is not hurt by the heat of the arc, but other materials might be used without departing, of course, from the spirit of my invention or without changing 15 materially the result obtained.

I claim:

1. In an arc lamp electrode, means for changing the color of the arc when one of the electrodes has been consumed to a certain fixed point and means for subsequently extinguishing the arc.
2. An arc lamp electrode comprising a metallic shell, a plug contained therein and embedded in the body thereof, said plug being made up of a material which when exposed to the action of the arc changes its

color and a lower insulation plug which extinguishes the arc.

3. An arc lamp electrode comprising a metallic shell, a plug contained therein and 30 embedded in the body thereof, said plug being made up of a material which when exposed to the action of the arc changes its color, and an insulating plug beneath supporting said color plug. 35

4. An arc lamp electrode comprising a conducting body, a plug contained therein embedded in the body thereof and removed from the normal arcing point, said plug being made up of a material such that when 40 exposed to the action of the arc it changes the color of the arc, an insulating plug adapted to interrupt the current and extinguish the arc when the color plug has been burned away. 45

In testimony whereof, I affix my signature in the presence of two witnesses this 26th day of January, 1914.

CHARLES W. DAKE.
